CLAIM

The ornamental design for an edge surround for
speaker, as shown and described.

DESCRIPTION

FIG. 1 is a perspective view of a edge surround for
speaker showing our new design;

FIG. 2 is a enlarged front elevational view thereof;

FIG. 3 is a enlarged side elevational view thereof, the
opposite side being identical;

FIG. 4 is a rear elevational view thereof; and,

FIG. 5 is a perspective view thereof.

The broken line showing of speaker and speaker box are
for illustrative purposes only and forms no part of the
claimed design.

FIG. 1

FIG. 4

FIG. 2

FIG. 3

FIG. 5
